CONVERTIBLE COLLAR FOR SHIRTS
OR THE LIKE

Samuel G. Payne, New Bedford, Mass.

Application December 28, 1948, Serial No. 67,607

7 Claims. (Cl. 2—116)

1

The subject of this invention is a novel and valuable attached collar for apparel garments of various kinds, as sport shirts, coats or jackets, raincoats, topcoats or overcoats especially for being worn in inclement weather, etc. The importance of the invention, and its special advantages, for comfort and/or protection as well as for style, in such relations for example as those just enumerated, will be appreciated from what follows in explaining the invention as herein shown embodied, by way of illustration but not by way of limitation, in connection with a man's sport shirt when used as an outer garment and for wear with or without a coat or jacket.

The present invention, for the first time so far as I am aware, provides a collar structure which, while attached to or built into the garment, is readily and perfectly convertible from an informal yet pleasingly arranged sports collar into a more formal medium high turn-down collar at once highly comfortable and of dressy aspect, and vice versa; and a collar structure which, furthermore, and in either case, whether arranged as a formal collar or as an informal or sports collar, lies perfectly flat, and when worn with a tie automatically is caused by the drawing up of the tie to assume a markedly improved appearance as compared with collars acting according to the principle of compromise shortly below referred to—which is to say, in the latter connection, when the top of the shirt is closed as by its top button thereby to establish a space between the points where the collar joins the garment, and when a tie is used and is drawn up to not more than comfortable snugness, said space closes until the collar meets in front at the now raised fold line. Thereby, and because the new collar as above presents a medium high neck which is at once very comfortable and of dressy appearance, and further because of the uniquely pleasing lie of the new collar when arranged as a sports collar, what may fairly be said to be broadly a new article of manufacture is provided, wholly avoiding all the troubles and objections characteristic of previously proposed so-called convertible attached collars, and notably obviating a major defect in that such a previous collar when arranged as a sports collar and attempted to be worn with a tie has the appearance of an abnormally low, unpleasingly over-size collar and generally giving a sloppy rather than a stylish casual effect.

So-called convertible attached collars as heretofore proposed have apparently been devised according to a principle of compromise as between

2

the desiderata in the case of a formal collar and in the case of a sports collar. As will be seen later, the new collar of the present invention is more akin to the collar typically made in the tailoring trade than to the collar typically made in the shirt trade.

While I preferably employ a stiffener insert, as buckram or the like, for a most important new and useful purpose, this insert radically differs from inserts as heretofore proposed; that is, whereas previous proposals have aimed at establishing a controlled or predetermined fold line, or some like such provision, as to establish a strong fold line in one location and a relatively weakened fold line in another location, my collar may be folded along any selected one of a plurality of possible lines at different places on the collar when it is to be worn in the same way but by different persons. One of the features of my insert is that it is cut in a special way on the bias, thereby, I have found, to make it self-conforming to various postures.

In combination with this insert, and desirably also in combination with another auxiliary insert preferably of small expanse than the first-named insert, other important features are present.

One of these features acts to prevent stretch between certain points spaced along the collar, as will later be explained, thereby to keep the central longitudinal portion of my new collar of a predetermined minimum length when the collar is worn either open or closed. Another of these features, preferably present, is the novel concept of so cutting and stitching together the sections of textile material or the like for providing a plural-ply collar structure that the length of some or all of said sections along a line extending substantially centrally longitudinally of the collar is less than their lengths at portions thereof spaced in both directions laterally of the collar from said line; this differential length feature preferably in part obtained by making the inner and outer plies of the collar structure each of two individually cut subdivisions stitched together at a midpoint along the length of the collar, these subdivisions at their ends thus stitched together having both such ends incut in a manner suggestive of a shallow lazy-V.

A further feature of the present invention is the manner of cutting what is termed in the shirt trade the slope at the neck portion of each front section of the main body of the garment, and a corresponding manner of cutting the collar structure at the length subdivisions thereof to be applied to said slope at each of the two front

sections of the main body of the garment; that is, in sharp contradistinction to the previous practice of curvilinearly extending such a slope, I extend the slope substantially rectilinearly and preferably along an absolutely straight line.

Various other features and advantages of the invention will become apparent or pointed out hereinafter.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a view showing the upper portion of a man's outer shirt equipped with a collar structure pursuant to the present invention, with the garment spread as flat as possible along the collar, and looking at the back of the shirt from the outside thereof.

Fig. 2 is a view similar to Fig. 1, but looking at the inside of the garment; and with the left front section of the main body of the shirt unnaturally spread to show a normally hidden preferred detail of construction.

Fig. 3 fragmentarily shows the garment as seen in Fig. 2 but with said unnaturally spread condition corrected to show said left front section as normally arranged at the inside thereof.

Fig. 4 fragmentarily shows the manner of cutting of a piece of the shirting material, to provide at its upper portion the neck adjacent portions of one of the front sections; and illustrating a straight cut of both slopes according to the invention, these slopes in positional relationship to the previous curvilinearly cut slopes indicated in dot and dash lines.

Fig. 5 is a composite view, showing the two like but reversely cut cloth pieces employed for establishing each of the two outer plies of the new collar structure.

Fig. 6 shows such a ply, spread as flat as possible, following seaming together of the two pieces of Fig. 5 along their in-cut edges contiguously placed in Fig. 5.

Fig. 7 is a view looking at the opposite side of the ply shown in Fig. 6, such side of the ply (assuming it to be the ply to be at the outside of the collar structure as spread flat in Figs. 1 and 2) being its inner side; this Fig. 7 also, in accordance with said assumption, showing said ply after there has been stitched thereto the already mentioned smaller insert, the latter being shown in Fig. 8, as originally cut, but before being rearranged as shown in Fig. 7.

Fig. 8 shows said smaller insert, as so originally cut, with this cutting inclusive of a central lateral slit, for permitting substantially triangular portions of this insert along opposite sides of said slit to be overlapped as indicated in Fig. 7.

Fig. 9 shows the already mentioned insert of buckram or the like, this also having a lateral central slit.

Fig. 10 is a view showing the last-named insert rearranged to impart a substantially triangular spread at said slit, thereby to lengthen the bottom length of said insert.

Fig. 11 illustrates the pile up of all the plies componental of the collar (except one of the two outer plies of such pile up—this latter, however, fragmentarily indicated in dot and dash lines), preparatory to stitching together all said plies, with said two outer ones each inside out, and so

that after said stitching is completed the assembly may be rearranged to have said two outer plies right side out; this stitching applied all around the assembly except along the boundary thereof at the bottom of Fig. 11.

Fig. 12 is an enlarged detail view, being a section taken on the line 12—12 of Fig. 2.

Fig. 13 is a like view, being a section taken on the line 13—13 of Fig. 2.

Fig. 14 shows the appearance of the shirt front with the parts arranged to provide a dress collar.

Fig. 15 is a similar view, but with the parts arranged to provide a sports collar.

The double hatched areas of Figs. 5, 7-9 and 11 indicate the run of the warp, that is, how certain important cuts are to be made on the bias to the straight of the goods.

Referring to the drawings now in more detail, a conventional shirt body construction is illustrated, comprising the common double back-yoke incorporating an outer yoke ply 20 and an inner yoke ply 21. Also, there is a back section 22, a left front section 23 and a right front section 24. Two of the yoke seams are indicated at 25, 25. The shirt construction as so far described is, as just stated, conventional; in which connection it is to be emphasized that the garment to which the new collar is to be attached need not have a yoke and the front and back joining seam or seams may be at the shoulders or any other place found desirable.

However, at this point referring to Fig. 4, showing a portion of the left front section 23 of the main body of the garment, it is to be noted that the slope 26 is cut straight, as contradistinguished from the usual curvilinearly extended slope as indicated in dot and dash lines at 27. The reference number 26 is also used in Fig. 2 to indicate there the location of said slope, the same extending from about the point indicated in Fig. 2 at 28 to the point there indicated at 29.

Before next proceeding to a description of the new collar itself, another feature of the shirt illustrated should be explained; that is, the provision of the slots 30 of Fig. 4. The purpose of slots 30 is to allow the left front section 23 to be folded vertically aligning the slots before employing the customary stitching indicated at 32 for attaching the collar to the shirt; said stitching 32 being also used, at the portion thereof indicated at 33, for closing the upper end of the inturned facing 34 to be at the inner side of the left front section 23, the latter is for carrying buttonholes such as indicated at 35, 35 in Fig. 3. With said stitching 33 terminating at the point marked 36 in Fig. 2, a pleat formation 37 is formed of the material between the slots 30 (compare Figs. 2 and 4). The meeting edges of the front section 23 inward of the meeting slots are attached to the bottom edge of the collar, with the straight edge 23^a, see Fig. 4, forming one-half of the respective yoke seam 25. This feature of the invention may be availed of for augmenting the really beautiful effect obtained when the new collar is arranged as a sports collar as shown in Fig. 15. The inturned facing 38 for the right front section of the main body of the garment, where the shirt is to have a convertible collar pursuant to the invention will also be cut and made as just described in connection with the inturned facing 34; it being noted that the facing 34, carrying said buttonholes 35, and also the facing 38, as for carrying buttons such as indicated at 39, 39, are projected beyond the meeting point of the base of the collar and the shirt.

The facing 38 has its top edge turned inward and secured to the base of the collar along the line C by stitches (not shown) similar to the stitches 33 used to secure the top edge of the facing 34 in position, see Fig. 2.

Referring next to the collar itself, and at this point first to Figs. 5 and 6, which is comprised of two outer plies 46 and 51 each preparatorily made of two like pieces 40 and 41. Each of the outer plies is made by stitching the respective pieces 40 and 41 together at their shallow-V incut ends 40^a and 41^a; each such V having preferably straight legs; and the said stitching running a locus indicated by the dot and dash lines 40^b and 41^b, thereby to provide a seam 42 which on one side of the ply (which is to be the outer face of the collar) appears as in Figs. 1, 2, 6, 14 and 15, and which on the other side of said ply (to be the directed inwardly side of the collar assembly) appears as in Fig. 7. The pieces 40 and 41 are cut so that the straight of the goods is parallel to the slanted ends of such piece, these ends marked 40^c and 41^c in Fig. 5.

The next step is to attach to outer ply 46, with the latter arranged as in Fig. 7, a lesser auxiliary ply or insert 43 such as shown in Fig. 8. This smaller insert 43 has been satisfactorily made of an ordinary plain-weave fairly light weight textile material, and is cut to have a long straight side 43^a, and to taper from its central portion toward its opposite ends by being given a central somewhat convexly rounded bottom edge portion smoothly merging into two straight and upwardly diverging terminal bottom edge portions 43^c. Laterally centrally thereof the insert 43 is slit as indicated at 44, this slit extending almost all the way across the width of the insert. The preferred proportions of the insert 43, relative to the outer ply 46 made as explained in connection with Figs. 5 and 6, is indicated in Fig. 7.

In said Fig. 7, the outer ply 46, which ply may be assumed to be that one of the two outside plies of the collar which is to be at the outside of the collar when arranged as in Figs. 1 and 2, is shown as lying flat as in Fig. 6 but with the inseamed marginal portions at the seam 42 uppermost so that these marginal portions will for the time being face inwardly of the collar assembly. Against what, therefore, is later to be the inside surface of said ply is placed the piece 43, arranged as shown in Fig. 7, that is, with triangular portions of the material of the piece 43 overlapping due to displacement of the opposite sides of the slit 44 as indicated at 44^a and 44^b. The securing of the piece 43 to said ply is by a single line of stitching 45.

After attaching the piece 43, the ply 46 is laid on a flat surface with the piece 43 facing downward. Next the outer ply 51 is laid on top of the ply 46 with its inturned marginal portions at the seam 42 uppermost.

The next step is to add to the structure of Fig. 7, a stiffener ply 47, as one of buckram or the like, such as shown in Fig. 9. This piece 47, shaped substantially as shown, is cut so that its bottom straight edge 47^a is at a 45° bias to the straight of the goods. The stiffener ply 47 is laid on top of the outer ply 51.

Laterally centrally thereof, and starting at said edge, the stiffener ply 47 has a slit 48. The slit 48 extends only over approximately slightly less than one-half of the width of the ply 47, where, as is desirable, the collar is made so that when it is later arranged as a dress collar, the collar at the back thereof will have its outer

downturned portion of a trifle greater width than the width of its inner upstanding portion and traversed by the entirety length of the slit 48. Then the line of fold given to the collar to arrange it as a dress collar will not have to be made intersectingly of said slit. The preferred proportions of the stiffener ply 47, relative to the super-imposed outer plies 46 and 51, is indicated in Fig. 11. Before the stiffener ply 47 is stitched in place, it is rearranged to establish a triangular opening at the slit 48, to obtain an important advantage as will be explained in connection with Fig. 10.

Referring to said Fig. 11 in more detail, it will be noted that the stiffener ply 47, when rearranged as to its slit 48 as just explained in connection with Fig. 10 and when placed on the ply 51 as in Fig. 11 (with said ply head spread at its upper portion to flatten out its ruffling similar to that shown in Fig. 7), may be deposited on said ply to match along its bottom edge portions 47^a the bottom edges of the plies 46 and 51 and also to cause the stiffener ply 47 to match along its main slanted end edges 47^b the main slanted end edges 40^c and 41^c of the plies 46 and 51. This ply 47, however, is cut so as not to extend to the extreme outer ends of the terminal portions or horns 56' of the ply 51, and also desirably so as along its top to parallel but not quite extend to the upper undulatory top edge portion 51'' of the respective outer ply 51. Now, it will be noted, the spread at the slit 48 of the piece 47 is opposite the portions of the piece 43 overlapped at the slit 44 of the latter, and with said spread nearly if not exactly matching the extent of said overlapped portions of the piece 43, a practically uniform thickness at such area is provided.

With the plies 43, 46, 51 and 47 stacked as in Fig. 11, a single stitching is applied to the stack along the two slanted ends thereof and along the undulatory top thereof, as pursuant to the dot and dash line 49 (compare Figs. 5 and 11). This stitching is indicated at 49' in Fig. 12. It may further be noted at this point that the dot and dash line 50 of Fig. 5 indicates the locus of the line of stitching 32, already discussed, whereby the completed collar is attached to the upper portion of the shirt.

The next step is to turn the collar structure inside out, thereby to arrange the parts as in Fig. 12, and as shown in Figs. 1, 2, 14 and 15; preparatory to attaching the collar structure to the shirt by the line of stitching 32 as already explained. Turning is accomplished by moving the outer ply 46 over the top edge of the collar so that its attached ply 43 finally faces the stiffener ply 47.

Following or prior to said attachment, but after the turning of the collar structure inside out, a line of stitching 52 of shallow inverted V extension is sent through all the four plies of the collar structure; this stitching 52 serving to tack down the top edge (43^a, Fig. 8) of the smaller insert 43. Note that the apex (52^a, Fig. 2) of such V is at a height just a trifle less than the height of the central point along a possible fold line indicated in dot and dash at 53 in Figs. 1 and 2; this line when used resulting in the formation of a dress collar having all the advantages aforesaid and as shown in Fig. 14.

In applying the stitching 52 it is desirably made long enough so that one end subdivision (52^b, Fig. 2) thereof may serve to tack down the upper portion of the inturned facing 38, and

so that the other end subdivision (51^a, Fig. 1) thereof may serve to tack down the upper portion of the inturned facing 34. This is an economy feature; in which connection it may be explained that in most cases the inside long edge of said facing is placed at the selvage of the cloth to save an operation of finishing at what otherwise would be a raw edge.

The already mentioned unusually attractive appearance of the collar when arranged as a sports collar is shown clearly in Fig. 15. The collar, however worn, has the center of its fold line at substantially the same location, that is, substantially as indicated at A in Fig. 2.

With a slope and the matching part of the collar cut as above in a straight line, the collar lies perfectly flat when pressed, or when the skirt is open to the second top button or even with the shirt closed at the top button. The bias construction permits the outer portion of the collar to stretch sufficiently to present a medium high neck, very comfortable and of dressy appearance, especially true when a tie is worn. The feature illustrated in connection with Figs. 5 and 6 shapes the collar so that as a dress collar it stands properly erect, yet so that as a sports collar it assumes naturally the unusually effective drape shown in Fig. 15. The lesser insert 43, particularly when tacked down along its top edge as explained, by the stitching 52, is primarily if not solely for the purpose of preventing stretch between the points marked A and B and between said point A and the point B' in Fig. 2; thus maintaining the collar size and keeping the central longitudinal portion of the collar the shortest when the collar is worn either open or closed.

As hereinabove first stated, the invention is applicable to other garments than shirts; for instance, jackets or coats. The new collar is particularly valuable for inclusion in a raincoat or other outer coat to be worn in inclement weather. In such a case, the collar points would desirably be shortened, and could be given a rounded or any style change without departing in any way from the invention.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A structure for a collar to be permanently attached to the main body of a garment and then to be convertible from a dress collar to a sports collar and vice versa, said structure including two outer plies one to be at the inner side and the other at the outer side of the collar when spread flat, and a stiffener insert between said plies, said insert being substantially coextensive in expanse with said plies and being laterally slit across approximately one half of the width of the collar when spread flat, said slit being extended in from the longitudinal edge of said stiffener insert which is attached to said body, the portions of the material of said insert along opposite sides of said slit being spread to form an inverted V-shaped notch, a portion of the collar along its longitudinal edge, and where the collar is attached to said body, being cut straight, said insert being of buckram or the like cut at approxi-

mately a 45° bias to the straight of the goods, said outer plies being cut longitudinally at a bias to the straight of the goods, each of said outer plies being comprised of two like but reversely arranged end aligned elongated sections having adjacent V-shaped re-entrantly cut end edges seamed together.

2. A structure for a collar to be permanently attached to the main body of a garment and then to be convertible from a dress collar to a sports collar and vice versa, said structure including two outer plies one to be at the inner side and the other at the outer side of the collar when spread flat, and a stiffener insert between said plies, said insert being substantially coextensive in expanse with said plies and being laterally slit across approximately one half of the width of the collar when spread flat, said slit being extended in from the longitudinal edge of said stiffener insert which is attached to said body, the portions of the material of said insert along opposite sides of said slit being spread to form an inverted V-shaped notch, a portion of the collar along its longitudinal edge, and where the collar is attached to said body, being cut straight, said insert being of buckram or the like cut at approximately a 45° bias to the straight of the goods, said outer plies being cut longitudinally at a bias to the straight of the goods, each of said outer plies being comprised of two like but reversely arranged end aligned elongated sections, having adjacent V-shaped re-entrantly cut end edges seamed together and a less extensive and less stiff auxiliary insert between said stiffener insert and that one of said plies which is to be the outer ply of the collar when spread flat.

3. A structure for a collar to be permanently attached to the main body of a garment and then to be convertible from a dress collar to a sports collar and vice versa, said structure including two outer plies one to be at the inner side and the other at the outer side of the collar when spread flat, and a stiffener insert between said plies, said insert being substantially coextensive in expanse with said plies and being laterally slit across approximately one half of the width of the collar when spread flat, said slit being extended in from the longitudinal edge of said stiffener insert which is attached to said body, the portions of the material of said insert along opposite sides of said slit being spread to form an inverted V-shaped notch a portion of the collar along its longitudinal edge, and where the collar is attached to said body, being cut straight, said insert being of buckram or the like cut at approximately a 45° bias to the straight of the goods, said outer plies being cut longitudinally at a bias to the straight of the goods, each of said outer plies being comprised of two like but reversely arranged end aligned elongated sections, having adjacent V-shaped re-entrantly cut end edges seamed together and a less extensive and less stiff auxiliary insert between said stiffener insert and that one of said plies which is to be the outer ply of the collar when spread flat, said auxiliary insert being substantially triangular and of small altitude compared to its base length and being placed in the collar structure with such base length at said longitudinal edge of the collar and with its portion of greatest width adjacent to the slit of the first-named insert.

4. A structure for a collar to be permanently attached to the main body of a garment and then to be convertible from a dress collar to a

sports collar and vice versa, said structure including two outer plies one to be at the inner side and the other at the outer side of the collar when spread flat, and a stiffener insert between said plies, said insert being substantially coextensive in expanse with said plies and being laterally slit across approximately one half of the width of the collar when spread flat, said slit being extended in from the longitudinal edge of said stiffener insert which is attached to said body, the portions of the material of said insert along opposite sides of said slit being spread to form an inverted V-shaped notch, a portion of the collar along its longitudinal edge, and where the collar is attached to said body, being cut straight, said insert being of buckram or the like cut at approximately a 45° bias to the straight of the goods, said outer plies being cut longitudinally at a bias to the straight of the goods, each of said outer plies being comprised of two like but reversely arranged end aligned elongated sections having adjacent V-shaped re-entrantly cut end edges seamed together and a less extensive and less stiff auxiliary insert between said stiffener insert and that one of said plies which is to be the outer ply of the collar when spread flat, said auxiliary insert being substantially triangular and of small altitude compared to its base length and being placed in the collar structure with such base length at said longitudinal edge of the collar and with its portion of greatest width adjacent to the slit of the first-named insert, said auxiliary insert adjacent to its said portion of greatest width being laterally slit.

5. A structure for a collar to be permanently attached to the main body of a garment and then to be convertible from a dress collar to a sports collar and vice versa, said structure including two outer plies one to be at the inner side and the other at the outer side of the collar when spread flat, and a stiffener insert between said plies, said insert being substantially coextensive in expanse with said plies and being laterally slit across approximately one half of the width of the collar when spread flat, said slit being extended in from the longitudinal edge of said stiffener insert which is attached to said body, the portions of the material of said insert along opposite sides of said slit being spread to form an inverted V-shaped notch, a portion of the collar along its longitudinal edge, and where the collar is attached to said body, being cut straight, said insert being of buckram or the like cut at approximately a 45° bias to the straight of the goods, said outer plies being cut longitudinally at a bias to the straight of the goods, each of said outer plies being comprised of two like but reversely arranged end aligned elongated sections having adjacent V-shaped re-entrantly cut end edges seamed together and a less extensive and less stiff auxiliary insert between said stiffener insert and that one of said plies which is to be the outer ply of the collar when spread flat, said auxiliary insert being substantially triangular and of small altitude compared to its base length and being placed in the collar structure with such base length at said longitudinal edge of the collar and with its portion of greatest width adjacent to the slit of the first-named insert, said auxiliary insert adjacent to its said portion of greatest width being laterally slit, said slit starting at said base of the auxiliary insert and extending almost over

the entirety of the width of the last-named insert.

6. A structure for a collar to be permanently attached to the main body of a garment and then to be convertible from a dress collar to a sports collar and vice versa, said structure including two outer plies one to be at the inner side and the other at the outer side of the collar when spread flat, and a stiffener insert between said plies, said insert being substantially coextensive in expanse with said plies and being laterally slit across approximately one half of the width of the collar when spread flat, said slit being extended in from the longitudinal edge of said stiffener insert which is attached to said body, the portions of the material of said insert along opposite sides of said slit being spread to form an inverted V-shaped notch, a portion of the collar along its longitudinal edge, and where the collar is attached to said body, being cut straight, said insert being of buckram or the like cut at approximately a 45° bias to the straight of the goods, said outer plies being cut longitudinally at a bias to the straight of the goods, each of said outer plies being comprised of two like but reversely arranged end aligned elongated sections having adjacent V-shaped re-entrantly cut end edges seamed together and a less extensive and less stiff auxiliary insert between said stiffener insert and that one of said plies which is to be the outer ply of the collar when spread flat, said auxiliary insert being substantially triangular and of small altitude compared to its base length and being placed in the collar structure with such base length at said longitudinal edge of the collar and with its portion of greatest width adjacent to the slit of the first-named insert said auxiliary insert adjacent to its said portion of greatest width being laterally slit, said slit starting at said base of the auxiliary insert and extending almost over the entirety of the width of the last-named insert, the portions of the material of the last-named insert along opposite sides of its slit being overlapped.

7. A structure for a collar to be permanently attached to the main body of a garment and then to be convertible from a dress collar to a sports collar and vice versa, said structure including two outer plies one to be at the inner side and the other at the outer side of the collar when spread flat, and a stiffener insert between said plies, said insert being substantially coextensive in expanse with said plies and being laterally slit across approximately one half of the width of the collar when spread flat, said slit being extended in from the longitudinal edge of said stiffener insert which is attached to said body, the portions of the material of said insert along opposite sides of said slit being spread to form an inverted V-shaped notch, a portion of the collar along its longitudinal edge, and where the collar is attached to said body, being cut straight, said insert being of buckram or the like cut at approximately a 45° bias to the straight of the goods, said outer plies being cut longitudinally at a bias to the straight of the goods, each of said outer plies being comprised of two like but reversely arranged end aligned elongated sections having adjacent V-shaped re-entrantly cut end edges seamed together and a less extensive and less stiff auxiliary insert between said stiffener insert and that one of said plies which is to be the outer ply of the collar when spread flat, said auxiliary insert being substantially triangular and of small altitude com-

pared to its base length and being placed in the collar structure with such base length at said longitudinal edge of the collar and with its portion of greatest width adjacent to the slit of the first-named insert, said auxiliary insert adjacent to its said portion of greatest width being laterally slit, said slit starting at said base of the auxiliary insert and extending almost over the entirety of the width of the last-named insert, the portions of the material of the last-named insert along opposite sides of its slit being overlapped, said auxiliary insert being tacked down along its downwardly diverging upper sides, thereby to prevent stretch of the collar structure for maintaining the central

5

15

longitudinal portion of the collar the shortest when the collar is worn either open or closed.
